(57) **CLAIM**

The ornamental design for a writing device, as shown and described.

DESCRIPTION

FIG. 1 is a front perspective view of a writing device showing my new design, the back view not being shown as it does not form part of the design;

FIG. 2 is a front view thereof;

FIG. 3 is right side view thereof;

FIG. 4 is a left side view thereof;

FIG. 5 is a top view thereof; and,

FIG. 6 is a bottom view thereof.

Features that are shown in equal sized broken lines form no part of the claimed design.
